PAPER ROLL SUPPORT

Arthur A. Kottmann, Davenport, Iowa, assignor
to The Bettendorf Company, Bettendorf, Iowa,
a corporation of Maryland

Application October 6, 1950, Serial No. 188,709

6 Claims. (Cl. 242—68)

1

This invention relates to paper roll supports for wrapping machines and has for its object to provide a support upon which a paper roll can be quickly and easily mounted for rotation on the support and upon which the roll can be accurately positioned with respect to the machine to which the paper is delivered.

In the support of the present invention the main supporting element is a tube rigidly attached at its inner end to a rigid part of the machine frame and having its outer end free to receive a paper roll. Inner and outer rotatable roll carrying units are provided for supporting engagement with opposite ends of the roll, the roll carrying units being mounted on the tube and the outer roll carrying unit being removable over the free end of the tube to permit a paper roll to be placed upon the tube. The roll carrying units are mounted for relative adjustment on the tube so that they can have clamping engagement with the paper roll, the relative adjustment of the roll carrying units being effected by a screw shaft within the tube. The roll carrying units include roll carrying members mounted on anti-friction bearings and one of the units carries an adjustable friction brake acting on the roll carrying member of the unit to apply as much resistance to rotation as may be necessary to prevent overrunning.

Reference should be had to the accompanying drawings forming a part of this specification in which:

Figure 1 is a top plan view of the support with one end broken away and shown in section;

Fig. 2 is a side elevation of the roll supporting tube and roll carrying units;

Fig. 3 is a fragmentary longitudinal section on an enlarged scale taken on the line indicated at 3—3 in Fig. 1; and

Fig. 4 is a transverse vertical section taken on the line indicated at 4—4 in Fig. 3.

In the accompanying drawings a fragment 1 of a machine frame is shown and to the frame 1 there is rigidly attached the inner end of a tube 2 which provides a paper roll receiving support. Within the tube 2 and substantially coaxial therewith there is mounted a screw shaft 3 which in the modification of the invention herein illustrated is provided with screws 4 and 5 adjacent its inner and outer ends, the screws 4 and 5 being right and left hand screws for simultaneously moving members in threaded engagement therewith in opposite directions. The shaft 3 is journaled at its inner end in a bearing member 6 mounted in the inner end of the tube and,

2

adjacent the outer end of the tube, has a bearing collar 7 attached thereto which rotatably fits within the outer end of the tube 2. A detachable spring locking ring 8 mounted in the outer end 5 of the tube 2 limits outward movement of the shaft 3. The shaft 3 projects beyond the outer end of the tube 2 and has a handgrip member 10 attached thereto. The handgrip member is 10 tubular and has a transverse pin 11 to afford engagement with the forked end of a hand crank which may be employed for turning the shaft when desired. However, the screws 4 and 5 have coarse threads and the required adjustments can ordinarily be made by turning the 15 shaft by means of the handgrip 10. The inner end of the handgrip 10 bears against the outer end of the tube 2 and is of the same diameter as the tube, the handgrip having a tapered shoulder 12 to facilitate the placing of a paper roll on the 20 tube.

Nuts 14 and 15 are mounted on the screws 4 and 5 and the tube 2 is provided along the length of the screws 4 and 5 with longitudinal slots 16 and 17 that receive portions of the nuts in the 25 form of keys 18 and 19 fixed to the nuts 14 and 15 and slidably fitting in the slots. Roll carrying units for engagement with the inner and outer ends of a paper roll are mounted on the tube 2 and these units are relatively adjustable longitudinally of the tube to clamp a paper roll between them.

Collars 20 and 21 are slidably mounted on the tube 3 and carry rotatable roll carrying members 22 and 23 which engage with opposite ends of the paper roll. The two roll supporting units comprising the slidable collar and rotatable roll carrying member have substantially identical roll engaging members, each of the roll carrying members having an inner tapering tubular portion 24 which closely surrounds the tube 2 inwardly of the collars 20 and 21, and each of the roll carrying members 22 and 23 has an enlarged outer tubular portion 25 surrounding the inner end of the collar upon which it is mounted, roll engaging shoulders 26 being provided between the enlarged outer portion 25 and the inner tapered portion 23 of the roll carrying member. Thrust ball bearings 27 are interposed between the enlarged portion 25 of the roll carrying members and the carrying collars 20 and 21.

The inner collar 20 is secured to the key portion 18 of the inner nut 14 by means of a screw 29. The key 19 is secured to the outer nut 15 by means of screws 19a. The outer roll carrying 55 unit is secured to the outer nut 15 by a quickly

releasable latch so that the unit may be quickly and easily removed from the tube to permit mounting of a paper roll. The latch is in the form of a radially slidable pin 30 that engages in a recess 31 in the key 19. The pin 30 is slidably mounted in a tubular guide 32 attached to the collar 21 and is pressed toward its locking position by a spring 33 mounted within the tubular guide 32. A suitable handle member 34 is attached to the outer end of the pin 30 so that the pin can be readily lifted out of engagement with the key 19 to permit the outer roll carrying unit comprising the collar 21 and roll support 23 to be removed over the free outer end of the tube 2. After a paper roll has been mounted on the tube 2 and the outer roll carrying unit has been replaced on the tube, the paper roll can be clamped between the carrying units by actuation of the screw shaft 3.

When the two roll carrying units are moved one toward the other the tapered ends 24 of the carrying members 22 and 23 enter the core of the paper roll, guiding the ends of the roll into engagement with the shoulders 26 which clamp the roll. For clamping the roll it is only necessary that one of the carrying units be screw actuated, but when it is desired to center the roll with respect to the machine to which the paper is fed as well as to clamp the roll, the two roll carrying units are attached to the nuts on the right and left hand screws 4 and 5, so that when the shaft 3 is turned the two units are moved simultaneously toward a central median plane, centering the roll with respect to that plane.

It is usually desirable to retard rotation of the paper roll sufficiently to overcome the momentum of the roll and prevent overrunning when pull on the paper being withdrawn is discontinued. To this end a brake arm 35 is pivoted to the outer collar 21 and has its inner end portion overlying the enlarged inner portion of the roll carrying member 23. The brake arm 35 is pivoted to a bracket 36 attached to the collar 21, and carries a friction shoe 37 that engages with the periphery of the enlarged portion 25 of the roll carrying member. Means is provided for yieldingly pressing the shoe 37 against the roll carrying member and for varying the pressure exerted on the shoe. The adjustable pressure applying means includes a radially disposed screw 38 attached to the collar 21 and bracket 36 and passing through an aperture in the arm 35. A spring 39 is interposed between the outer face of the arm 35 and a nut 40 on the screw 38. The pressure exerted by the spring 39 on the shoe 37 can be regulated by adjusting the nut 40 which is secured in adjusted position by a lock nut 41.

It is to be understood that in accordance with the provisions of the patent statutes, variations and modifications of the specific devices herein shown and described may be made without departing from the spirit of the invention.

What I claim is:

1. A paper roll support comprising a frame, a tube attached at one end to said frame and having a free roll receiving end, said tube having longitudinal slots, a shaft journaled within said tube and having a right-hand screw and a left-hand screw spaced apart longitudinally within the tube, a nut on each screw, a collar slidable on said tube adjacent each nut, means connecting said collars to said nuts through said tube slots to cause the collars to move longitudinally with the nuts inwardly toward one another and

5 outwardly away from one another and to hold the collars and nuts against rotation on the tube, opposed roll carrying members, each having a tubular outer end portion surrounding the inner end of one of said collars, a tubular inner end portion of less diameter than the outer end portion and closely overlying the tube inwardly of the collar and an annular shoulder portion connecting said tubular portions, and a ball thrust bearing interposed between said outer end portions of said roll carrying members and said collars.

10 2. A paper roll support comprising a frame, a tube attached at one end to said frame and having a free roll receiving end, said tube having longitudinal slots, a shaft journaled within said tube and having a right-hand screw and a left-hand screw spaced apart longitudinally within the tube, a nut on each screw, a collar slidable on said tube adjacent each nut, means connecting said collars to said nuts through said tube slots to cause the collars to move longitudinally with the nuts inwardly toward one another and outwardly away from one another and to hold the collars and nuts against rotation on the tube, opposed roll carrying members, each having a tubular outer end portion surrounding the inner end of one of said collars, a tubular inner end portion of less diameter than the outer end portion and closely overlying the tube inwardly of the collar and an annular shoulder portion connecting said tubular portions, a ball thrust bearing interposed between said outer end portions of said roll carrying members and said collars, a brake mounted on one of said collars and engaging the tubular outer portion of the roll carrying member, and adjustable means for pressing said brake against said roll carrying member.

15 3. A paper roll support comprising a frame, a tube attached at one end to said frame and having a free roll receiving end, said tube having longitudinal slots extending inwardly from its attached and its free ends, a shaft journaled in said tube and having a right-hand screw and a left-hand screw spaced longitudinally thereof, a nut on each screw having a portion guided in one of said longitudinal slots, two spaced roll supporting units each comprising a collar slidable on said tube and a roll engaging member having a tapered tubular roll engaging inner end and an enlarged tubular outer end rotatably mounted on said collar, and a locking member carried by each collar and engaging the guided portion of a nut, the locking member of the collar adjacent the free end of the tube being mounted for movement to a position clear of the nut and tube to permit the unit to be removed over the free end of said tube.

20 4. A paper roll support comprising a frame, a tube attached at one end to said frame and having a free roll receiving end, said tube having a longitudinal slot, a screw journaled in said tube, a nut on said screw having a portion extending into said slot and provided with an exteriorly facing recess, a removable roll supporting unit comprising a collar slidable on said tube and a roll carrying member rotatably mounted on said collar, a radially movable locking member slidably mounted on said collar and engageable in said nut recess to detachably fasten said collar to said screw, and a spring pressing said locking member toward locking position.

25 5. A paper roll support comprising a frame, a tube attached at one end to said frame and having a free roll receiving end, said tube having a

longitudinal slot, a screw journaled in said tube, a nut on said screw having a portion extending into said slot and provided with an exteriorly facing recess, a removable roll supporting unit comprising a collar slidable on said tube and a roll carrying member rotatably mounted on said collar, a radially movable locking member slidably mounted on said collar and engageable in said nut recess to detachably fasten said collar to said screw, a brake arm pivotally connected to said collar and overlying a portion of the roll carrying member mounted on the collar, a brake shoe attached to said arm, a spring acting on said arm to press the shoe against the roll carrying member, and means for adjusting the tension of the spring.

6. A paper roll support comprising a frame, a tube attached at one end to said frame and having a free roll receiving end, said tube having a longitudinal slot, a shaft journaled in said tube and projecting past its free end, a screw on said shaft within said tube, a handgrip member attached to the projecting end of said shaft, one end of said handgrip member being adjacent said

tube and of approximately the diameter of the tube, said member tapering outwardly from said end, a nut on said screw having a portion slidably engaging said slot, a removable roll supporting unit comprising a collar slidable on said tube and a roll carrying member rotatably mounted on said collar, and a movable locking member carried by said collar and engageable with said slot engaging portion of said nut to detachably fasten said collar to said nut.
